UNITED STATES PATENT OFFICE.

RALPH C. WALLING, OF REDELM, SOUTH DAKOTA.

CORN-DRYING RACK.

Application filed March 7, 1928. Serial No. 259,861.

The present invention is directed to improvements in corn drying racks.

The primary object of the invention is to provide a rack so constructed that a number 5 of ears of seed corn can be conveniently supported thereby in order that the ears will be maintained in separated condition to permit the free circulation of air.

Another object of the invention is to provide a rack of this nature which can be conveniently suspended and the ears impaled 10 upon prongs disposed upon opposite sides of the rack.

Another object of the invention is to provide a device of this kind which is simple in 15 construction, efficient in operation and one which can be manufactured at a small cost.

While the drawing illustrates a preferred 20 embodiment of the invention it is to be understood that in adapting the means to meet specific needs and requirements the design may be varied and such other changes in the minor details of construction may be resorted 25 to within the scope of the invention as claimed, without departing from the spirit thereof.

For a full understanding of the invention and the merits thereof, reference is to be 30 had to the following description and the drawing hereto attached, in which,—

Figure 1 is a front view of the rack.

Figure 2 is a sectional view on line 2—2 of Figure 1.

Figure 3 is a detail perspective view.

Corresponding and like parts are referred 35 to in the following description and designated in the several views of the drawing by like reference characters.

The rack consists of upper and lower 40 strands 4, the opposed ends of which are provided with eyes 5 which terminate in spurs 6. Arranged between the strands are shanks 6' which have their ends provided with eyes 7,

the eyes of the shanks 6' being interlocked with the eyes 5 of the strands 4, while the remaining eyes of the series of shanks are interlocked with each other. The eyes 7 terminate in spurs 8 and it will be noted that upon reference to Figure 2 that the spurs are inclined upwardly and extend from opposite 50 sides of the rack in order that the ears 9 can be supported upon both sides of the rack.

Horizontal wire strands 10 are engaged in the interlocked eyes 5 and 7. These strands engage in the eyes with sufficient friction to 55 maintain the series of strands and shanks in proper spaced relation.

It will be observed that when the ears are impaled upon the spurs that each ear will be so supported as to not contact with the adjacent ear, thus insuring a free circulation of 60 air in order that the corn kernels will be uniformly dried to preserve the same in proper condition.

A rack constructed in the manner set forth 65 is capable of being rolled when not in use, and conveniently suspended for use when unrolled by securing the upper strands 4 in any suitable manner to a beam or other hanger. Further, it will be observed that the racks 70 can be woven in determined lengths and widths and then cut into sections of any desired lengths.

Having thus described the invention, I 75 claim:

A rack of the class described comprising upper and lower strands having opposed 80 terminal eyes, shanks arranged between the strands and having eyes upon their ends, the eyes of certain of the shanks being interlocked with the eyes of the strands, the remaining eyes of the strands being interlocked with each other, and horizontal strands engaged in the interlocked eyes.

In testimony whereof I affix my signature.

RALPH C. WALLING. [L. s.]
